UNITED STATES PATENT OFFICE.

WILLIAM H. DEHN, OF CLEVELAND, OHIO.

WASTE CONTROL FOR BASINS.

Application filed November 30, 1921. Serial No. 518,841.

To all whom it may concern:

Be it known that I, WILLIAM H. DEHN, a citizen of the United States of America, residing at Cleveland, in the county of Cuyahoga and State of Ohio, have invented certain new and useful Improvements in Waste Controls for Basins; and I hereby declare the following to be a full, clear, and exact description of the invention, such as will 10 enable others skilled in the art to which it pertains to make and use the same.

This invention relates to new and useful improvements in waste controls for basins, lavatories and the like and particularly to 15 the type known as pop-up waste devices.

One object of my invention is to provide means for lifting the stopper a considerable distance above the waste opening thereby insuring a quick and positive drainage to the 20 bowl.

A further object of my invention is to provide means which will act automatically to lock the lifting lever after the stopper has been raised and thereby positively sustain the stopper in its raised position until 25 the pull up handle is again operated.

My invention therefore consists in the features of construction and combination of parts hereinafter described in the specification, particularly pointed out in the claims 30 and illustrated in the accompanying drawings.

Referring to the accompanying drawings, Fig. 1 is a view partly in section showing a 35 portion of a lavatory with a device embodying my invention applied thereto. Fig. 2 is a detail view, mostly in central section, showing the lifting lever locked in its raised position. Fig. 3 is a similar view showing 40 the lifting lever in its lower position. Fig. 4 is a detail view showing a top plan of the lifting lever and a portion of the operating and locking mechanism.

Again referring to the drawings 10 represents the bowl of a lavatory of the usual 45 type having the flange or table portion 11 and splash plate 12. In the bottom of the bowl is formed the usual drainage opening 13 which extends down through the boss 14 which is formed integral with the bowl. The bowl may also be provided with the 50 overflow passageway shown at 15 arranged in the usual manner. The upper end of a T-fitting 16, preferably of the globular type, 55 is secured to the boss 14 and the lower end of said fitting 16 receives the end of the

waste pipe 17. The stopper for closing the waste opening 13 in the bottom of the bowl is shown at 18 and is of the customary disk type having a stem portion 19 which extends 60 down into the fitting 16.

In the side connection of the fitting 16 is secured one end of a pipe section 20 and on the other end of said pipe section is rigidly supported an oblong casing. This casing 65 comprises in general a neck portion 21 which is cylindrical in form and a hollow end or head portion 22, the sides of which are flat and the said head portion is arranged at an angle to the cylindrical or neck portion. In 70 the end of the head portion is formed an opening 23. In the neck portion 21 is fitted a packing gland 24 which carries a water proof fiber packing ring 25. In front of the packing gland is arranged a snug fitting 75 sleeve 26 which has an internal flange 27 at its forward end. The stopper lifting lever comprises a spherical shaped portion 30 from which a short arm 31 extends forwardly into the head portion 22 and a long 80 arm 32 extends rearwardly through the pipe section 20 and into the fitting 16 underneath the stem 19 of the stopper 18. At the forward end of the neck portion 21 is formed an annular shoulder 33 and between this 85 shoulder 33 and the sleeve 26 is arranged a strong coiled spring 34. This spring is arranged to press against the sleeve 26 which causes the internal flange 27 to engage with and press the spherical portion 30 of the 90 stopper lifting lever against the packing ring 25 thereby forming a water tight joint.

In the upper part of the head portion 22 is pivotally mounted a bell-crank lever 36 the long arm of which extends out through the opening 23 in said head portion. A link 37 connects the short arm of the bell-crank lever with the long arm 31 of the stopper 95 lifting lever.

In the flange 11 of the bowl is mounted 100 a gland or fitting 40 in which is mounted a rod 41. The upper end of the rod 41 is provided with a handle or knob 42. An escutcheon 43 is preferably arranged over the top of the fitting 40 to provide the usual 105 ornamentation. To the long arm of the bell-crank lever 36 where it projects from the head 22 is secured one end of a rod 44 and the other end of said rod is screw headed. The adjacent ends of the rods 41 110 and 44 are operatively connected together by a turn-buckle 45.

The operation of my device will be readily understood. When the stopper is in its closed position the stopper lifting lever and the bell-crank lever 36 will be in the position shown in Fig. 3 with the connecting links 37 buckled. Now if the rod 41 be pulled up by means of the knob 42 the long arm of the bell-crank lever 36 will be drawn up and the short arm will be swung down. 10 Now as the short arm of the bell-crank lever starts to swing down the link 37 remains buckled and the short arm 31 of the lifting lever is swung down and the long arm 32 is of course swung up. The long arm 32 engages with the stem 19 of the stopper 18 shoving it up and thereby raising the stopper 18 from the waste opening 13. The short arm 31 of the lifting lever will continue to move down until the end thereof 20 is below the axis of the lifting lever and also the short arm of the bell-crank lever will be below the axis of the bell-crank lever. On the continued movement of the short arm of the bell-crank lever the link 25 37 will straighten out and will assume the position shown in Fig. 2. When in this position it will be observed that the pivoted connections of the link 37 with the short arm of the bell-crank lever and the short 30 arm of the lifting lever are approximately in a straight line with the axis of the bell-crank lever. The short arm of the lifting lever is therefore locked against upward movement and the long arm, of course, is locked against downward movement. The 35 long arm will therefore positively sustain the stopper in its open position until the operating rod is again actuated. When the operating rod is shoved down the long arm 40 of the bell-crank lever is swung down thereby swinging up the short arm and as the short arm swings up it causes the link to buckle. As soon as the link is buckled the lifting lever is unlocked and as the short 45 arm of the lifting lever is drawn up through its connection with the short arm of the bell-crank lever the long arm of the lifting lever swings down permitting the stopper to move down to its closed position.

50 What I claim is:—

1. In a device of the character described, the combination with a bowl having a waste outlet and a stopper for closing the said outlet of a fitting extending down from said

waste outlet, a pipe section mounted in the 55 side connection of said fitting, a casing supported by said pipe section, said casing comprising a cylindrical portion and a head portion, a stopper lifting lever mounted in said cylindrical portion, said lever having 60 a spherical shaped body portion, a sleeve mounted in said casing and surrounding the spherical portion of said lever, said sleeve having an internal flange at its forward end of less diameter than the diameter of the 65 spherical portion of said lever, a coiled spring mounted in said casing and exerting a constant pressure against said sleeve, a gland mounted at the opposite end of said 70 casing and carrying a packing ring adapted to bear against the spherical portion of the stopper lifting lever and means for operating said lever.

2. In a device of the character described, the combination with a bowl having a waste 75 outlet and a stopper for closing said waste outlet of a fitting extending down from said waste outlet, a pipe section mounted in the side connection of said fitting, a casing supported by said pipe section, said 80 casing comprising a cylindrical portion and a head portion, a stopper lifting lever mounted in said cylindrical portion, said lever having a spherical shaped body portion, a sleeve mounted in said casing and surrounding the spherical portion of said 85 lever, said sleeve having an internal flange at its forward end of less diameter than the diameter of the spherical portion of said lever, a coiled spring mounted in said 90 casing and exerting a constant pressure against said sleeve, a gland mounted at the opposite end of said casing and carrying a packing ring adapted to bear against the spherical portion of the stopper lifting 95 lever, an actuating lever mounted in said casing at a point above the axis of the stopper lifting lever, a link connecting the adjacent arms of said levers and a rod connected to the free arm of the actuating 100 lever.

In testimony whereof, I sign the foregoing specification, in the presence of two witnesses.

WILLIAM H. DEHN.
